UNITED STATES PATENT OFFICE

2,354,683

OXIDATION OF SECONDARY ALCOHOLS

David C. Hull, Kingsport, Tenn., assignor to
Eastman Kodak Company, Rochester, N. Y., a
corporation of New Jersey

No Drawing. Application May 1, 1942,
Serial No. 441,269

3 Claims. (Cl. 260—596)

This invention relates to the direct oxidation of organic compounds, particularly hydroxy compounds exemplified by secondary alcohols. This invention is particularly adapted to the direct oxidation of such secondary alcohols to ketones and esters, and will be described hereinafter.

This invention is a continuation-in-part of my allowed application Serial No. 228,822, filed September 7, 1938, now Patent No. 2,287,803.

As set forth in my parent application aforesaid, prior to my invention in the prior art in order to convert hydroxy compounds to other products it has been necessary to employ relatively high temperatures such as temperatures between 200° C. and 500° C. In more detail, for example, in the instance of converting a secondary alcohol into a ketone, in accordance with the prior art procedure the secondary alcohol in the vapor phase would be contacted with a solid catalyst at relatively high temperatures of several hundred degrees centigrade. Proceeding in accordance with prior art practice possesses certain disadvantages exemplified by the use of the aforesaid high temperature. There are also various attendant disadvantages such as low yield, and the requirement that large quantities of heat be supplied, since the aforesaid high temperature processes generally are endothermic. Also in many instances the production of the desired product necessitated several steps. This is illustrated in the instance of converting a secondary alcohol to an acid which requires dehydrogenation to the ketone and then the oxidation of ketone in the vapor phase. The employment of several stages introduces greater opportunity for losses and involves the handling of combustible material in which the fire hazard is exceptionally high due to the elevated temperatures involved.

In my Patent No. 2,287,803 I have described treatment particularly adapted for conversion primary alcohols which overcomes the aforesaid disadvantages, and in the present application I describe a direct oxidation procedure particularly adapted for the treatment of secondary alcohols which represents a substantial improvement over prior art procedure employed for the treatment of such compounds.

This invention has for one object to provide a direct oxidation process particularly adapted to the treatment of organic compounds having a hy-

droxy group in the secondary position, as for example on an intermediate carbon atom, as the α or β position, etc. Another object is to provide a process permitting the direct conversion by oxidation of secondary alcohols to ketones. A still further object is to provide an oxidation process which may be operated at relatively low temperatures. Still another object is to provide a process for oxidizing organic compounds which, 5 after it has been started, is more or less self maintaining as respects heat input. Still another object is to provide a novel catalyst solution for carrying out the aforesaid processes. Other objects will appear hereinafter.

I have found that the aforesaid secondary hydroxy compounds may be directly oxidized at a relatively low temperature under liquid phase conditions to ketones and other oxidation products. Examples of some of these secondary compounds are compounds such as isopropyl and secondary butyl alcohols from which may be obtained by my direct oxidation process ketones and acids and, also, some esters. Also there may be treated in a similar manner various secondary amyl alcohols, secondary hexyl alcohols, secondary heptyl alcohols, and secondary octyl alcohols. 15

Under preferred conditions, as I will point out in detail hereinafter, I would directly oxidize such secondary compounds in the presence of an acidic catalyst solution containing as a catalyst a metal compound from a metal of the 8th group of the periodic system. However, as will be pointed out, various other metal compounds will satisfactorily function, hence, the broader aspects 20 of my invention embrace other catalysts. In any event, irrespective of the particular catalyst metal employed, the catalyst solution may contain a certain amount of the alcohol being processed and the catalyst solution would preferably be in an activated condition both before and during use.

In further detail in preferred operation I would prepare a catalyst solution essentially comprising an organic acid (either a common lower aliphatic acid, an acid of the type which would be obtained from the oxidation process or the like) having dissolved therein one or more of the metal compounds which is to be employed as a catalyst. The catalyst solution would have present a content of water which is preferably small and, also, 25

in some instances a small content of an alcohol of the type undergoing processing.

In preparing the catalyst solution various compounds of the catalyst metal may be incorporated into the acid solution as long as a compound is employed which goes into solution satisfactorily. That is, considering cobalt as an example of the catalyst metal, there could be employed cobalt oxides, cobalt acetate, or other ester salts or other compounds, such as strontium acetate, aluminum acetate, silver acetate, chromium acetate and uranium acetate. After the catalyst materials are incorporated in the acid or other solvent, as for example a mixture of acid and alcohol, the solution would be vigorously treated with air, oxygen, or other oxidizing medium, preferably under some pressure, and a content of a carbonyl compound also supplied along with the air introduction. For example, the introduction of a content of a lower aliphatic aldehyde such as butyraldehyde and the like aids in the activation. Various other aldehydes could be employed such as propionaldehyde and acetaldehyde.

The aforesaid activation treatment would be carried out at a temperature below the boiling point of the particular catalyst solution and generally temperatures under 100° C. are quite satisfactory, usually until a substantial content of the catalyst metal has become converted to a valence higher than its lowest valence, or until the gaseous medium containing free oxygen (such as air) being introduced has so permeated the entire solution that the solution is on the verge of effervescence.

The preferred catalyst metal would be the same as described in my Patent No. 2,287,803, namely, cobalt and related metals. As described in said parent application, a content of cobalt acetate could be dissolved in acetic acid and the resultant solution activated, as already described.

While cobalt and the metals referred to in my copending parent application are preferred, other catalyst metals may be employed in the treatment of secondary alcohols. Secondary alcohols appear to be less difficult to oxidize than the other alcohols described in my Patent No. 2,287,803. I have further found that various alkaline earth and alkali metal compounds may be employed in preparing the catalyst solution, amongst which may be mentioned lithium, beryllium, sodium, potassium, rubidium, caesium, calcium, strontium, barium, magnesium, and zinc, which are more fully described in my Patent No. 2,287,803. As is there indicated the oxides, acetates, butyrates, or other derivatives of these metals which are capable of being put into solution and activated, may be employed.

Still other metals which may be employed are metals from the aluminum group and the rare earths. Also metals from the platinum group are described in Mellor's Chemistry at page 641, or metals of the refractory type such as chromium, molybdenum, tungsten, and the like operate satisfactorily.

In general I have found that in the oxidation of secondary alcohols the catalyst solution may comprise an acidic solution preferably of a lower organic acid having dissolved therein a metallic compound, which solution is capable of activation with an aldehyde, as above described.

The catalyst solution, whatever its particular composition, but which in accordance with my preferred embodiment would include a cobalt compound, would be placed in the oxidation ap-

paratus and preferably activated therein by the treatment with the oxidizing medium and aldehyde, as already described.

Oxidation apparatus the same as that described in my Patent No. 2,287,803 may be employed for the treatment of secondary alcohols, in accordance with the present invention, or apparatus such as shown in Hasche U. S. Patent No. 2,159,988 may be employed. In general the apparatus should comprise suitable means for bringing the secondary alcohol to be oxidized in contact with a liquid catalyst solution also in contact with the oxidizing medium containing free oxygen. Suitable provisions would be made for controlling the temperature, preferably by having a plurality of coils positioned within the reaction chamber so that the coils are immersed in the catalyst solution. However, the jacketed oxidation units or a combination of jacketed units with internal coils may be employed.

Also preferably there would be suitable means for dispersing the oxidizing medium and other components fed to the unit; however, since provision for this is fully described in Hasche Patent 2,159,988, further description herein is unnecessary.

Assuming, therefore, that suitable oxidation apparatus is supplied with a catalyst liquid capable of activation and which has been activated by oxygen and aldehyde, secondary alcohols may be oxidized as follows: The alcohol, together with preferably a slight excess of the oxidizing medium, would be blown into the unit so as to bubble through the catalyst solution in intimate contact with the oxidizing medium. Also from time to time, or if desired in a small continuous stream, a certain amount of lower aliphatic aldehyde may be supplied to the process for assisting in maintaining the catalyst activity.

I have found that irrespective of the particular metal compound employed with the aforesaid activation, oxidizing the medium and aldehyde, either before carrying out the oxidation step of the process or in conjunction therewith, greatly improves the oxidation, extends the life of the catalyst solution and renders possible the utilization of a very large variety of metal compounds as catalysts.

The oxidation procedure, in accordance with my invention, concerns the conversion of secondary alcohol to ketone and ester. Also, certain other products are formed, as will be described in further detail under the specific examples which follow.

The products which are formed may be removed from the process by withdrawing a portion of the catalyst solution from the upper part of the unit or some other convenient point and subjecting it to distillation or other treatment for separating the reaction products, after which the catalyst solution may be returned to the process, or by temperature regulation so that there is a constant volume of catalyst solution with a quantity equal to the weight of the products formed, boiling off continuously.

For example, assuming the secondary alcohol treated was isopropanol, the resulting catalyst solution, after the oxidation, would contain acetone or certain other reaction products. The solution may be substantially continuously removed from the oxidation, subjected to distillation for volatilizing off the acetone, and the resulting stripped catalyst solution returned to the process.

For a still further understanding of my inven-

tion reference will be had to the following examples. The first three examples, which are set forth in tabular form, refer in particular to the carrying out of my process employing the preferred catalyst, namely, a catalyst solution containing an activated cobalt compound.

Example VI

In accordance with this example secondary hexyl alcohol of the formula

5 was processed in the presence of a catalyst solu-

Examples	Compound	Catalyst	Total weight alcohol fed	Total weight aldehyde fed	Materials recovered			Per cent converted to—			Per cent yield
					Weight ketone	Weight ester	Weight acid	Ester	Ketone	Acid	
I.....	Isopropyl alcohol.....	Cobalt.....	686.7	936	125.3	88	782	7.53	18.98	18.2	91.2
II.....	do	do	827.0	400	114.5	130.8	504	9.25	14.30	9.45	96.0
III.....	Sec. butyl alcohol.....	Cobalt nickel.....	705	1,762	349.0	32	191	2.84	50.8	28.16	70.9

¹ Includes 4 g. propionic acid and 87 g. acetic acid.

² Includes 0.55% conv. to propionic acid and 7.61% conv. to acetic acid.

The foregoing examples were carried out at temperatures between approximately 30° C. and 60° C. obtained by the supplying of cooling medium to coils positioned within the reaction chamber. The process was operated so that the catalyst solution was maintained in the liquid phase and at constant volume, the temperature being so regulated that the same amount of liquid distills off as is added and after the process has been placed in operation, it generates sufficient heat to be self-maintaining, particularly if the catalyst is kept in an active condition.

In the examples which follow the procedure was similar to that indicated in the foregoing examples except that wider temperature ranges were employed, as between -5° C. and 90° C. By applying pressure higher temperatures up to 140° C. or higher may be employed and still operate under liquid phase conditions. However, in general not over a few pounds positive pressure is preferred and utilization of low temperatures is advantageous for preventing polymerization as well as avoiding the necessity of any substantial heat input, as discussed in the first part of the present application.

Example IV

In accordance with this example secondary amyl alcohol of the formula

was passed through the oxidation unit in contact with an activated catalyst solution and with a slight excess of air as an oxidizing medium. This secondary alcohol was converted approximately between 1% to 10% to secondary amyl ester, 20% to 70% to methyl propyl ketone, 2% to 20% propionic acid, and 1% to 15% acetic acid. There are also varying traces of other acids, probably formic and butyric acids. The process was operated with sufficient cooling medium supplied to the coils to maintain the catalyst in a liquid condition.

Example V

In accordance with this example a secondary amyl alcohol of the formula

was processed in a manner analogous to the immediately preceding example. This secondary alcohol was converted 1% to 10% to secondary amyl acetate, 20% to 70% to diethyl ketone, and similar amounts of acid such as propionic and acetic acid, as described in the preceding example.

20 tion containing a mixture of cobalt and nickel, the catalyst having been thoroughly activated prior to the contacting of the secondary hexyl alcohol therewith. Substantially simultaneous with the introduction of the secondary hexyl alcohol there was also introduced air as the oxidizing medium and intermittently acetaldehyde was supplied. The hexyl alcohol was converted approximately up to 10% to the secondary hexyl ester, 20% to 70% to ethyl propyl ketone, and a 25 content of propionic, acetic, and butyric acid formed. It appears that the propionic acid predominated, amounting to between 2% and 30%.

Example VII

30 In accordance with this example secondary hexyl alcohol of the formula

35 was processed substantially similar to that described in the preceding example. There was obtained secondary hexyl ester up to 10%, 10% to 70% methyl butyl ketone, and varying amounts of acids as between 1% to 15% or 20% acetic and butyric acid. These acids may also have in admixture therewith small amounts of formic and valeric acid.

40 The preferred operating temperatures of the foregoing examples would preferably be under 100° C. if normal atmosphere pressure or only a slight positive pressure were applied. However, the reaction may be caused to proceed even at temperatures as low as a -5° C. and at temperatures above 100° C., particularly the higher temperatures when pressure is applied to the reaction 45 as by throttling the outlet conduit at the top of the oxidation unit.

45 The highest yields appeared to be obtainable when my preferred cobalt or cobalt nickel catalyst was employed, namely, a catalyst as described in my Patent No. 2,287,803. However, satisfactory results may be obtained when utilizing alkali or alkaline earth metal compounds as the catalyst material. As long as the catalyst was in an activated condition this appeared to 55 exert as much influence on the satisfactoriness of the oxidation as the choice of any specific catalyst metal or mixture of metals.

55 The unconsumed secondary alcohol leaving the oxidation unit may be recovered by distillation 60 or in some other way.

60 While air was used as the oxidant in the preceding examples, relatively pure oxygen and ozone may likewise be employed. However, air being the most economical and since my oxidation process functions satisfactorily therewith.

particularly if a catalyst liquid is in a fully activated condition, the employment of more concentrated or vigorous oxidizing mediums is optional.

With respect to proportions in my preferred operation, as above indicated I would supply sufficient oxidizing medium to the process so that some unused oxidant, but usually less than 50% excess, would appear in the effluent gases from the process. As to the incorporation of aldehyde such as acetaldehyde, propionic aldehyde, butyraldehyde, or other aldehydes for catalyst activation, the choice of the particular aldehyde and amount thereof is governed by the particular components being processed. Preferably the aldehyde used for activation would be one which would become converted to a product such as will be produced in the oxidation reaction. As indicated, since all of the lower aliphatic acids may be produced by the oxidation process it is possible to employ any of the lower aliphatic aldehydes for activation media and to employ any of the lower aliphatic acids as the solvent medium in which to dissolve the metal compound for preparing the catalyst solution.

With respect to quantity of alcohol employed, this does not appear to be critical and various quantities appear to function satisfactorily in my process. In practice, however, I would generally apply my process to the treatment of commercial sources of alcohol. For example, in the instance of isopropyl alcohol the so-called commercial azeotropic mixture, namely, a mixture of isopropyl alcohol and water, would be processed and even considerably more dilute solutions may be treated, but due to their tendency to dilute the catalyst would not be preferred. That is, in my process a very dilute alcohol, such as dilute isopropyl alcohol, may be easily concentrated to the azeotrope by conventional procedure and the azeotrope fed to the process. Similar remarks apply to the other secondary alcohols, some of which form constant boiling mixtures with water. The alcohol, either in a dilute or concentrated condition as may be desired, may have in admixture therewith, or there may be supplied simultaneously or intermittently with the alcohol supply, a content of a lower aliphatic aldehyde, as already disclosed. In general at least 4% or 5% of the aldehyde would be preferred, and amounts up to 50% or 75% may be employed. The higher the amount of the aldehyde the higher the content of acid in the reaction product, also the lower the content of water produced which would tend to dilute the catalyst solution. In the event the catalyst solution becomes diminished in acid content and it is desired to build up the acid content, this can, for example, be accomplished by supplying aldehyde or increasing the content of aldehyde already being supplied. In the preceding examples the aldehyde supply varied from 5% to 50%, the larger quantities being supplied in the event the catalyst indicated loss of activation.

It is believed apparent from the preceding examples that I have provided a novel procedure whereby secondary alcohols may be converted to ketones and esters by oxidation at relatively low

temperatures, namely, temperatures such as those at which the secondary alcohols may be maintained under liquid phase conditions. The utilization of liquid phase conditions and relatively low temperatures not only involves less heat input, but the less severe conditions present fewer difficulties from apparatus destruction, fire hazard, and losses by heat polymerization.

It is also believed apparent from the foregoing that my invention is applicable to the oxidation of a number of secondary alcohols of which the foregoing examples are merely illustrative.

What I claim and desire to be secured by Letters Patent of the United States is:

1. A process for the direct oxidation of a lower aliphatic secondary alcohol to obtain the corresponding ketone which comprises treating a solution of a metal ion of a metal numbered 25-29, inclusive, of the periodic table in an aliphatic acid with an aldehyde and a gaseous oxidizing medium to form a catalyst solution, introducing material amounts of a lower aliphatic secondary alcohol and a lower aliphatic aldehyde into the activated catalyst solution, oxidizing the alcohol

20 of the resulting solution of catalyst, alcohol and aldehyde by treating said solution with a gaseous oxidizing medium, maintaining the temperature of the solution of catalyst, alcohol and aldehyde during its treatment with the gaseous oxidizing medium such that the solution is maintained in the liquid phase, and subsequently recovering the ketone produced.

2. A process for the direct oxidation of a lower aliphatic secondary alcohol to obtain the corresponding ketone which comprises treating a solution of a metal ion of a metal numbered 25-29, inclusive, of the periodic table in an aliphatic acid with an aldehyde and a gaseous oxidizing medium to form a catalyst solution, introducing

30 material amounts of a lower aliphatic secondary alcohol and a lower aliphatic aldehyde into the activated catalyst solution, oxidizing the alcohol of the resulting solution of catalyst, alcohol and aldehyde by treating said solution with a gaseous oxidizing medium, maintaining the temperature of the solution of catalyst, alcohol and aldehyde

35 during its treatment with the gaseous oxidizing medium such that the solution is maintained in the liquid phase, and subsequently recovering the ketone produced.

40 3. A process for the direct oxidation of a lower aliphatic secondary alcohol to obtain the corresponding ketone which comprises treating a solution of a cobalt salt in an aliphatic acid with an aldehyde and a gaseous oxidizing medium to form a catalyst solution, introducing material

45 amounts of a lower aliphatic secondary alcohol and a lower aliphatic aldehyde into the activated catalyst solution, oxidizing the alcohol of the resulting solution of catalyst, alcohol and aldehyde by treating said solution with a gaseous oxidizing medium, maintaining the temperature of the solution of catalyst, alcohol and aldehyde

50 during its treatment with the gaseous oxidizing medium such that the solution is maintained in the liquid phase, and subsequently recovering the ketone produced.

55 4. A process for the direct oxidation of a lower aliphatic secondary alcohol to obtain the corresponding ketone which comprises treating a solution of a cobalt salt in an aliphatic acid with an aldehyde and a gaseous oxidizing medium to form a catalyst solution, introducing material amounts of a lower aliphatic secondary alcohol and a lower aliphatic aldehyde into the activated catalyst solution, oxidizing the alcohol of the resulting solution of catalyst, alcohol and aldehyde by treating said solution with a gaseous oxidizing medium, maintaining the temperature of the solution of catalyst, alcohol and aldehyde during its treatment with the gaseous oxidizing medium at a temperature below 100° C. whereby the solution is maintained in the liquid phase, and subsequently recovering the ketone produced.

DAVID C. HULL.
